WRAPPING MACHINE

Godfrey Dalkowitz, New York, N. Y., assignor to
American Safety Razor Corporation, Brooklyn,
N. Y., a corporation of Virginia

Application September 17, 1934, Serial No. 744,294

18 Claims. (Cl. 93—2)

This invention relates generally to a method of wrapping flat articles, and coordinate therewith to a machine for carrying out such method.

While my method of wrapping is adapted for flat articles of many forms, it has been found to be of great advantage in connection with articles of substantially rectangular form such as safety razor blades.

The illustrative embodiment of a machine for carrying out my method of wrapping is adapted particularly for the wrapping of safety razor blades, which are of very thin sheet steel, and of a form basically rectangular, and includes means for positioning a blade in relation to a sheet of paper of peculiar shape, and for folding down protruding ends of the sheet over the exposed surface of the blade. As will be apparent, however, after the principles of my machine are fully understood, the same principles apply to the wrapping of other articles, and modification in detail is all that is necessary to adapt the machine for such other articles.

Among the general objects of my method of wrapping are the efficient and expeditious handling of the article and the wrapping material, resulting in a product which will be an assembly of article and wrapper of uniform size no greater than necessary for adequate protection, and of uniform and pleasing appearance, and affording adequate protection to the article, while also, where the article is one such as a razor blade, capable of injuring persons handling them, affording protection to such persons.

Coordinate therewith, among the objects of my invention is the provision of a wrapper of improved type.

Among the general objects of my machine is the provision of means for effectively carrying out all the steps enumerated in connection with my method.

Among the particular objects thereof may be mentioned the provision of improved means for presenting a wrapper to an unwrapped blade, the provision of means for receiving such wrapper and blade in a preliminary associated relation; the provision of means for successively folding down portions of the wrapper into the position necessary for the final associated relation of wrapper and blade, and the provision of means for creasing and folding portions of the wrapper at the proper points.

For the attainment of these objects and such other objects as will hereinafter appear or be pointed out, I have disclosed an illustrative em-

bodiment of my invention in the drawings, wherein:

Figure 1 is a view intended to illustrate the various steps in the process of applying a wrapper to a razor blade, the wrapper and the blade being shown in perspective;

Figure 2 is a side elevation of a portion of a wrapping machine for carrying out my method of wrapping, such parts of the machine as are entirely conventional having been either omitted or shown in dotted lines;

Figure 3 is a plan view of the portion of a wrapping machine shown in elevation in Figure 2;

Figure 4 is a view in perspective illustrating the arrangement for presenting a wrapper in the path of a razor blade to be wrapped;

Figure 5 is a sectional view taken on the lines 5—5 of Figures 2 and 3, looking in the directions of the respective arrows, and showing the arrangement for receiving the preliminarily associated blade and wrapper and for presenting them and passing them on to the folding devices for completing the wrapping operations;

Figure 6 is a view in perspective showing one of these folding devices;

Figure 7 is a sectional view on the lines 7—7 of Figures 2 and 3 looking in the directions of the respective arrows and showing the channel and guideway into which the wrapped blade is moved during the course of the folding operations;

Figure 8 is a section on the line 8—8 of Figure 3, looking in the direction of the arrows, illustrating the means for advancing the wrapped blade in the channel leading to the devices for further treating the wrapped blade;

Figure 9 is a sectional view on the lines 9—9 of Figures 2 and 3, looking in the directions of the respective arrows, showing means for creasing portions of the wrapper;

Figure 10 is a sectional view on the lines 10—10 of Figures 2 and 3, looking in the directions of the respective arrows, showing another portion of the channel and the means associated therewith for completing the folding operation;

Figures 11 and 12 are respectively sections on the lines 11—11 and 12—12 of Figures 2 and 3, looking in the direction of the respective arrows, showing successive stages of the wrapping operations and particularly the provision for causing one flap of the wrapper to be superposed on the other.

Figure 13 is a sectional view on the lines 13—13 of Figures 2 and 3, looking in the directions of the arrows, showing a section of the guide chan-

nel near its terminal portions, and, also, in dotted lines, a blade and wrapper assembly in its final form; and

Figure 14 is a perspective view intended to make clear the motions of the various parts of my machine in their relation to each other, conventional means for imparting the necessary motions to all the parts of my improved mechanism being shown.

10 In wrapping flat articles such as razor blades, it has hitherto been customary to take a wrapper of rectangular shape, position the blade within it, and then fold over the edges of the wrapper so as to overlie and completely enclose the blade. 15 Because of the rectangular shape of the wrapper, when the article was placed with its edges parallel to those of the wrapper, a problem was presented by the corner portions of the wrapper, at which there was excess material which had to be disposed out of the way, with the result that, 20 when it was attempted to do so by folding, these corner portions had to be overlapped and a construction involving many unnecessary layers of wrapping material resulted, which made the 25 wrapped blade thicker than necessary and which caused it to present an irregular unsightly appearance. Of necessity the process of wrapping was also complicated.

On the other hand, where the article and the 30 wrapper were positioned in a diagonal relation the flaps could not be made to overlap properly so as to secure the necessary protection for the article, unless again, portions of the wrapper were overlapped unnecessarily.

35 By referring to Figure 1, the various steps involved in my improved method of wrapping and the advantages thereof over the methods heretofore employed will be clearly understood. These steps have been indicated by the letters *a*, *b*, *c*, *d*, *e*, *f* and *g*.

40 At the extreme right of Figure 2 I have shown at *W* a wrapper, and at *R* a razor blade. The wrapper *W* is first of all interposed in the path of the blade and held stationary when blade and 45 wrapper have the relative positions shown in the figure at *a*, with one end of the blade positioned along the line at which it is desired to fold the wrapper so as to cause one flap thereof to lie over the blade. The arrow *20* indicates the feed motion of the wrapper in order to bring it into its 50 proper position, although it is understood of course that this is only by way of example, as the motion may be effected from other directions than the one shown. When the wrapper *W* is 55 properly positioned and is stationary in such position, for which purpose the wrapper feed rollers, as indicated at *F* in Figure 2 are positioned so as to release the wrapper when it reaches the correct position, the blade *R* is moved in the direction indicated by the arrow *22*, and in moving, 60 it pushes the wrapper against a forming device to be hereinafter described so that the wrapper is doubled up along the line *24*, with the body *26* of the wrapper positioned above the blade 65 and flat against it, and the flap *28* of the wrapper flattened against the blade underneath it. This position is shown at *b*. By mechanism to be hereinafter described the blade and wrapper assembly is now inverted, and this is illustrated in Figure 1 70 in which the assembly is shown as passing from the initial position *b* through an intermediate position *c* and into the final position *d* of this part of the process, by which the body *26* of the wrapper, which originally was folded flat against 75 the upper part of the blade now underlies the

same while the flap *28* overlies it and is at the trailing end of the blade instead of at the advancing end. Before the blade reaches the final position *d* just mentioned, the flaps *30*, *32*, and *34* are folded in relation to the body *26* of the 5 wrapper so as to stand upwardly substantially at right angles thereto. Suitable mechanism next 10 folds the flap *34* down flat against the blade and so that its end overlaps the end of the flap *28*, which are made of sufficient length for that purpose, and creasing mechanism next applies creases to the wrapper along the lines *36* and *38* which are positioned so as to be slightly spaced from the edges of the blade, whereby assurance will be obtained that the outermost portions of the 15 wrapper will be spaced from the cutting edges of the blade and injury to the shaving edges of the blade or to persons handling the wrapped blade will be prevented. This stage will correspond to position *e* of Figure 1. The final stages in the 20 wrapping operation involve a folding down of the side flaps *30* and *32* so that one of them, say *30*, overlies the other flap *32*, and for this purpose, as the figure shows at *f*, the folding of flap *32* is commenced first while the flap *30* is held upright, 25 and thereafter the flap *30* is released and folded down so that its end portions overlap the end portions of the flap *32*, as shown at *g* in Figure 1. The blade and wrapper assembly is now in its 30 final form and ready for the next operation, such as, for example, the application of an outer wrapper or label.

I will now pass to a description of a machine adapted to carry out the steps of the process just described. On referring to Figures 2 and 3, it 35 will be observed that my improved machine comprises first of all advancing means for the blades indicated in dotted lines and denoted by the letter *P* in Figures 2 and 3, which, however, forms no part of my invention, and a conventional mechanism for presenting the wrappers one at a time, indicated in dotted lines in Figures 2 and 3, and denoted by the letter *F*, which also is no part of my invention. Further adjunctive to my invention, without being a part thereof, is a stacking 40 arrangement *S* for holding the unwrapped razor blades, and for permitting them to drop one at a time into the path of the advancing means *P* and against a wrapper in the frame denoted as a 45 whole by the letter *A*.

At *B* I have shown a spider provided with jaws adapted for the reception of the associated blade and wrapper, such association resulting 50 from the action of the mechanism *P* which pushes a blade against a wrapper, causing the latter to 55 double over the blade, as will be explained hereinafter. This spider is moved intermittently as will be described more in detail hereinafter, and each movement of the spider rotates it through 60 ninety degrees. During the first ninety-degree 65 movement, the blade and wrapper newly received into the spider, are moved from the horizontal receiving position to an intermediate or vertical position, and during the second ninety degree movement, they are again moved into a horizontal position, which, however, is one in which the wrapper and blade assembly is inverted as compared to the initial horizontal position, while at the same time during said second movement the flaps *30*, *32* and *34* are preliminarily folded 70 into an upstanding position, described in connection with Figure 1, and shown at *d* in said figure. The pushing mechanism indicated at *C* now removes the blade and wrapper assembly 75 from the spider *B*, and into a series of elements, 75

referred to collectively by the letter D, which perform the final folding operations described in connection with Figure 1, and pushes the completely wrapped blade along the channel L and into the mechanism for storing or further processing, indicated by E, and forming no part of the present invention.

The cycle of operations of the machine, particularly in relation to the timing of the various movements, will now be described in connection with Figure 14, which shows, illustratively, mechanism for moving the various elements of my invention approximately in the proper timed relation. It is to be understood, however, that this showing is highly simplified so as to facilitate explanation, and that it does not embody the many refinements of an actual machine, such as, for instance, the use of cams instead of cranks, where the speed variation of a crank is not the ideal for the intended purpose.

On referring to Figure 14, it will be observed that the actuating mechanism is shown as comprising a main shaft O driven by a motor M. The shaft O carries a pair of cranks S and T disposed similarly in relation to each other, the crank T being connected by a link T¹ to a rocker arm U carried by the rockshaft V, which rockshaft through a rocker arm P¹ carried at its other end, serves to actuate the blade pushing mechanism P, as is clearly shown in the figure. The crank S on the other hand, as it turns, actuates a connecting rod K, designed to reciprocate the pushing mechanism C for advancing the wrapped blades. As will be later described, a portion of the pushing mechanism C is in the form of an extension serving to remove the blade and wrapper assembly from the spider B, which is fixedly mounted on a shaft T² that also carries the cam wheel of a Geneva stop motion fixed thereon, which, together with its actuating wheel, is indicated at Z in Figure 14, and which is driven through an intermediate shaft T³ from the main shaft O.

The timed relationship of the actuating mechanism in connection with Figure 14 may now be discussed as follows: When C and P move toward the left, the extension 90 of C, (see Figure 2) acts to remove a blade and wrapper assembly from the spider B, which is stationary, and at the same time P pushes a new razor blade against a wrapper and into the adjacent jaw of spider B. When C and P move backward to the right, the extension 90 of C moves backward toward the shaft T² so as to be positioned in back of the blade and wrapper assembly to be next pushed out of the spider B, and P similarly moves in relation to the stack S so as to be positioned in back of the next blade to be pushed out. While this is taking place, a fresh wrapper W has been fed into place, and the spider B has advanced a quarter turn so as to present toward the wrapper and empty blade and wrapper assembling jaw and to the opposite side a jaw containing a blade and wrapper assembly ready to be removed. The timing is so adjusted, however, that the extension 90 of C, which removes the blade from B, reaches its extreme right hand or rearward position before the blade and wrapper assembly about to be removed become positioned for such removal.

It will be noted that whereas a blade and wrapper assembly is inserted and another assembly is removed at each quarter turn of spider B, two quarter turns elapse before any particular assembly advances from its entrance position to its removal position. After removal of the blades

from B, they travel step-wise, in accordance with the motion of C, along the channel L leading from D and into the next adjacent mechanism E, and the final wrapping operations are effected while they travel along this channel. It will be understood that at each revolution of the main shaft O an unwrapped blade enters the spider B and a wrapped blade leaves the channel L, as will be described more in detail hereinafter.

G denotes the body or main frame of the machine, within which is supported the actuating mechanism as described in connection with Figure 14, and which serves to support the wrapping mechanism which is the subject of this application.

After this preliminary explanation, the elements comprised in the mechanism will be described in detail.

Referring to Figure 4 which illustrates in perspective that portion of my machine which has been referred to in connection with Figures 2 and 3, as A, it will be observed that to a portion 60 of the frame of the machine is attached a plate-like member 62 that is recessed to receive the projecting end flap 28 of the wrapper W. A plate 64 is positioned in front of the member 62 so as to prevent forward displacement of the flap 28 from its seat within the recess of member 62. A pair of elements 66 and 68, most clearly shown in Figure 2, provide a guideway wherein the wrapper as it leaves the rollers F is guided, so that ultimately its end flap 28 will enter the recess in 62 as already described. Members 62 and 66 are vertically spaced so as to leave a horizontal slit between them, this slit being intended for the passage therethrough of a razor blade S from the bed of the machine and into one of the jaws of the spider B. This is clearly shown in Figures 2 and 4. The position of the wrapper W is such that as the blade S passes through the slit it engages the wrapper at the junction of the flap 28 thereof with its body portion 26, that is to say, at that portion at which the fold is to be made in the wrapper.

Passing now on to the spider B it will be observed that the same comprises a hub 70 mounted in fixed relation on a shaft T², already mentioned in connection with the disclosure of Figure 14 as being actuated stepwise by the Geneva stop motion mechanism Z. Attached to each side of hub 70 is a cross shaped plate 74. Each arm of the plates 74 is slotted radially as indicated at 76 in Figures 2 and 5, thereby forming a space within which the blade and wrapper assembly may be received and for this purpose the shaft T² is mounted at such a level that the slits 76 of the horizontally positioned arms of plates 74 are aligned with the guideways for the blades or blade and wrapper assemblies on each side thereof.

In order to hold the blade and wrapper assemblies in position within the slits a resilient gripping jaw construction is used, which will be understood by reference to Figure 5 in conjunction with Figures 2 and 3. It will be observed from these figures that one surface of the jaw is formed by a pair of plates 78, one carried by each of the members 74 on the inside thereof. These plates are made removable and may be of hard, wear-resisting material. The other jaw 70 surface is constituted by a pair of resiliently hung elements 80, each of channeled conformation and adapted to slidably receive a member 74 within its channel, and held in place by a pair of screws 82 passing freely through bores 84 in plate 74 75

- and also through a plate 86 removably carried by said plate 74. Plate 86 has the function of preventing passage of the heads of the screws 82 therethrough and of acting as an abutment 5 for spiral compression springs 88 acting between plate 86 and element 80 so as to cause the said elements 80 always to press resiliently against the plates 78, or against a blade and wrapper assembly, if that is interposed.
- 10 It will be understood that as a blade and wrapper assembly is pushed forward into a jaw of spider B, the elements 80 will yield upward sufficiently to permit the entry of the blade and wrapper assembly therebetween and the plates 15 78, which entry is facilitated by the flare of the entrance portions indicated at 73 in Figure 2. The assembly will then be held in place by the spring pressure.

As a result of the motion of spider B, the 20 blade is next advanced through two quarter turns of the spider, as has already been described, and as a result of this movement, it reaches a position diametrically opposite to its entering position. The blade is also reversed during this 25 movement, so that flap 28 which at first was underneath the blade, and at its advancing end, is now uppermost and at the rear end of the blade. During this movement also, the flaps 34, 32 and 30 are caused to stand upright by contact with a certain element of that portion of the machine which has heretofore been designated collectively by D.

Removal of the blade and wrapper assembly is effected by the arm 90, forming a part of the 30 pushing mechanism C and extending upwardly into the space between the members 14 and in back of the blade and wrapper assembly when in position within the jaws. It will be observed that the inner or bottom walls 77 of the slits 40 76, which form stops for the blade and wrapper assemblies are spaced from the hub 70, and it is in this space between walls 77 and the periphery of the hub that the arm 90 is located prior to its removing motion. The reason for 45 the use of a pair of spaced members 14 will now be obvious, this being so in order to permit the free turning of the spider B, while the arm 90 moves backward and forward through the gap between the two side members 14 thereof.

50 Arm 90 is carried by a bracket 92 which is caused to reciprocate by the connecting rod K mentioned in connection with Figure 14. An extension 94 of this bracket, shown in the form of a straight bar, carries thereon, at intervals, 55 pusher members 96, the detailed construction of which is disclosed in Figure 8, and which serve to advance the blades along the track L. The extension 94 is supported at intervals from D as indicated at 98, in sliding relation thereto, 60 whereby it is free to slide back and forth.

Referring to Figures 7 and 8 it will be noted that each pusher member 96 carries at its upper end an element 100 pivotally mounted at 102 on the pusher member 96 and formed with an 65 upper inclined face 104. A spring 106 is interposed between 104 and 96 so that if the element 100 as it moves to the left in Figure 8 strikes an object, it will push the same toward the left, because contact of an extension 108 thereof with 70 member 96 prevents its yielding. On the other hand as it moves to the right, if it meets an obstruction positioned in the channel L, it will yield by pivoting about 102, whereby its nose or high portion 112 will be depressed permitting it to slide underneath the obstruction. The ex-

10 tension 108 will thereby be caused to move to the right, being free to do so and in this direction of motion does not act as a stop. For convenience of construction, as shown in Figure 7, one side of the pivot 102 may be carried by a 5 member 114, removably carried by 96.

15 Passing now to a consideration of the guide channel L, it will be observed on viewing Figures 2, 3 and 7 to 13 inclusive that the same comprises bed frame constituted by two parallel members 110 that are spaced from each other so as to permit the pushing elements 96 and 100 to move in the intermediate space. Members 110 are supported at a convenient point from the main frame G of the machine, as by a suitable 15 bracket 116.

Carried by the extensions 111 of the members 110 and aligned thereon are a succession of devices, heretofore referred to as D, which 20 complete the folding of the wrapper, and these will now be described in succession, commencing at the right hand end of the assembly D as shown in Figures 2 and 3.

25 As the blade and wrapper assembly is moved by the spider B from an upstanding position to the horizontal discharge position, the ends or flaps 30, 32 and 34 of the wrapper W, which project laterally from the spider B, come in contact with the edges of a folding device, shown in perspective in Figure 6, and in elevation and plan in 30 Figures 2 and 3 respectively, and comprising two side plates 118 and 120 and an arcuately formed piece 122 which is curved along a cylindrical surface concentric with the spider B. The piece 122 engages the flap 34 with its upper edge 124 at its 35 juncture with the body 26 of the wrapper and thereby folds it so as to bring it into the upstanding position shown in Figure 1 at d, and retains it in such a position until it reaches the lower edge 126 of the member 122. This lower 40 edge is positioned so as to leave a small space between it and the members 110, and the blade, as it is pushed out of the spider B, passes underneath the lower edge 126 and between the same and the members 110 with the result that the flap 45 34 is now folded flat down on the face of the blade and retained in such position by the said lower edge 126, and when the flap passes beyond the zone of action of 126, the flap is still kept in its downwardly folded position by means later 50 to be described. The member 122 is shown in the drawings as joined to the part 118 at its upper portion for purposes of support, while it is free of the part 120. This construction is illustrative merely as it is quite obvious that the part 122 55 might be supported otherwise than from the part 118, or on the other hand it might be supported from both 118 and 120. The particular advantages resulting from the construction shown is that the upstanding side flap 32 of the wrapper 60 may pass through the space 121 left between parts 122 and 120. A similar space 123 (see Figures 3 and 6) is left between parts 122 and 118 at the lower part of 122 to permit the passage of the flap 30.

65 After flap 34 is bent upward by edge 124 the motion of the spider B causes flap 30 to be engaged by the upper edge 128 of the part 118 and at the same time the upper edge 130 of the part 120 engages the flap 32 so as to bring these flaps 70 into a vertical position, as indicated at d in Figure 1. When the blade and wrapper assembly is discharged from the spider B, these flaps remain in their upstanding position due to contact with the members 118 and 120 and to the elasticity of 75

the paper, which retains the flaps resiliently against said members 118 and 120. The assembly next passes into a channel formed by the members 118 and 120 and guide members 132 and 134, mounted respectively on the pieces 118 and 120, and having inner portions 136 and 138, which serve to confine the flaps 30 and 32 in the narrow channels formed between them and members 118 and 120, whereby these flaps are kept positively 10 in upstanding relation. Lateral extensions 140 formed on the end portions of 136 and 138 and positioned in parallelism with the extension 111 of members 110 so as to leave a small space therebetween, engage the downwardly folded flap 34, and keep it in its downwardly folded position, the space being just sufficient to accomplish that purpose.

The blade and wrapper assembly continues in its passage between the members 118 and 120 20 until it reaches a pair of creasing rollers 144 and 146 positioned within the channel, and shown in detail in Figure 9. These rollers have their edges beveled and are inclined at an angle to the members 110 forming the bed of the channel, 25 so that the beveled edge projects directly into the corner formed at the meeting of parts 118 and 120 with the members 110. The rollers 144 and 146 are mounted for rotation on members 150 and 152, pivotally mounted at 154 and 156 on elements 158 and 160 carried by the members 118 and 120, and are resiliently urged into the corners of the channel and against the wrapper by the pressure of springs 162 and 164 suitably positioned between the pairs of members 150, 158 and 152, 35 160.

Rollers 146 and 148 serve to apply a crease, that is, to form a sharp bend, in the wrapper between the flaps 30 and 32 and the body 26 of the wrapper. Their action assures the formation 40 of creases slightly spaced from the shaving edges of the blade, so that in the finished assembly the razor blade edges will be spaced from the creases and thereby be adequately protected, and at the same time, a person handling the package will be protected against injury due to such spacing. 45 For example, where the width of a double edged razor blade from shaving edge to shaving edge is seven-eighths of an inch the creases may be spaced one inch or slightly less. In addition, the formation of the creases at these points by this 50 or similar mechanism assures a neat looking package.

The final stages of the wrapping operation include the folding down on the blade of the flaps 30 and 32 in such a manner that the flap 32 will 55 be first folded down to be followed by the flap 30 superposed thereon. For this purpose a pair of grooved guide members 166 and 168 is applied to the bed frame members 110, the function of which is to fold down the side flaps 30 and 32, and positioned between said members is an element 182, the function of which it is to prevent flap 30 from being folded flat on the blade until flap 32 has been at least partly folded down. 60 The construction of the members 166 and 168 clearly appears from Figures 11, 12 and 13, viewed in conjunction with Figure 3. Each of these members is provided with an undercut or recessed portion 172 which forms the side wall of 65 the guide channel. The walls of the two portions 172 together define a channel of uniform width, this width being just sufficient to contain the blade and wrapper assembly and to permit the same to slide therebetween. The upper walls of 70 the recessed portions 172 are flared inwardly as 75

indicated at 174, with a gradual diminution of the flare as the assembly advances, and the effect of this is shown in Figures 11, 12 and 13, in which the flaps 30 and 32 are shown bent downward slightly by the upper wall 174 of the recess, as in Figure 11, and then bent farther down as shown in Figure 12, and bent completely down as in Figure 13 which shows a section of the channel at which the undercut is no longer flared. Upon comparing these views with Figure 3, it will be 10 noted that because of this increase in flare of the undercut, the inner edges of members 166 and 168 are cut away in contour toward their right hand ends to form a channel increasing in width toward the right, or considered from the stand-point of the blade assembly, decreasing in width as the assembly advances. Grooves 176 may be provided in the pieces 166 and 168 and similar grooves 178 may be provided in the bed members 110 to accommodate any wrinkles or folds that 20 may be formed in the wrapper during the folding process, and thereby insure smoothness of action. These grooves run parallel to each other and to the walls 172.

The member 182 already mentioned, which is 25 shown as in the form of a vane, and the function of which is to cause flap 32 to fold down in advance of the folding down of the flap 30, is carried by an angular member 170, the horizontal leg of which is positioned between the pieces 166 30 and 168 at the entrance thereof and has the vane 182 mounted thereon. Member 170 is shown as supported from the bed 110 by a bracket member 180 to which the vertical leg of member 170 is attached. The action of vane 182 will be 35 understood from an inspection of Figures 11 and 12, which show consecutive sections through the horizontal leg of the member 170. In Figure 11, the flaps 30 and 32 are shown at the commencement of the downwardly folding operation while 40 in Figure 12, flap 32 has been folded down on the upper surface of member 170, whereas the flap 30 is prevented from lying down flat by the vane 182. As soon as the blade and wrapper assembly 45 passes beyond the limits of the member 170 the flap 30 is completely released, and, as a result of the action of the grooves in members 166 and 168, folds down over the flap 32 which has assumed a horizontal position in advance of the flap 30. This 50 last condition is illustrated in Figure 13, which represents a cross section through the wrapper and blade assembly in its final form.

It has already been mentioned that advance of the blade and wrapper assemblies along the channel of D is effected by the pusher elements 55 96, which are spaced at intervals along the channel and cause the advance of all the blade and wrapper assemblies within the channel by a distance equal to that of one blade at each operation of the pusher elements. 60

At each operation of the pusher elements 96, the advance blade and wrapper assembly, that is, the assembly at the left hand end of the chain of assemblies moving along the channel is moved into the succeeding mechanism, indicated in dotted lines and by the letter E in Figures 2 and 3. In these figures it is shown as a wrapping mechanism similar to the one forming the subject of this invention, and such as would be adapted to place an outer wrapper or label over the wrapper 65 applied by the machine disclosed herein. However, it will be obvious that the mechanism E may be of any type desired, in accordance with the character of the processing to which the blade and wrapper assembly is to be subjected. 70 75

While I have herein disclosed by way of example, one embodiment of my machine, it will be obvious that the same may assume many other forms as will be obvious to those skilled in the art, without departing from the spirit of the invention as defined in the appended claims, and it will also be obvious that the practice of my method of blade wrapping is not restricted to the operation of the machine herein disclosed.

Having thus described my invention and illustrated its use, what I claim as new and desire to secure by Letters Patent is:

1. Apparatus for wrapping razor blades comprising a wrapper positioning member for holding a wrapper across the path of an advancing razor blade so as to be engaged thereby and folded over the same so as to form a wrapper and blade assembly, an intermittently rotatable member having means therein for receiving and holding said wrapper and blade assembly while said member is in a stationary position, a guide channel for said assembly, means to remove said assembly from said member while it is in another stationary position and to push it into said guide channel, folding means for preliminarily folding portions of said wrapper into an intermediate position perpendicular to the body of the wrapper before the entry of said assembly into said channel, means for advancing said assembly along said channel, guide means for retaining said last-mentioned portions of said wrapper in said perpendicular position, means for causing other portions of said wrapper to assume an overlying relation to the blade, creasing means for creasing the line of junction of said perpendicular flaps with the body of the wrapper, means for retaining said overlying portions in said overlying relation to the blade, means for folding the perpendicular portions into an overlying position to the blade and to said first-mentioned overlying portions and means for preventing the folding down of certain of said perpendicular portions until the other perpendicular portions have been folded down so as to overlie the blade and means for receiving the completed blade and wrapper assembly after its passage through said channel.

2. In apparatus for wrapping razor blades: means for positioning a wrapper in the path of an advancing razor blade and for effecting an assembly of said blade and wrapper, intermittently moving means for receiving said assembly and stationary portions adapted to cooperate with said moving means for folding portions of said wrapper into a position perpendicular to the blade, a guide channel for said assembly, means for removing said assembly from said intermittently moving means while it is stationary and into said channel, and means, operative while said assembly is in said channel, for folding said perpendicular portions so that they overlie said blade, whereby a substantially flat blade and wrapper assembly will be produced.

3. A construction as defined in claim 2 in which the last-mentioned means effects the folding of various portions of the wrapper successively so that each folded portion overlies the blade and each portion of the wrapper previously folded.

4. In wrapping mechanism, means for forming creases in a wrapper, said means comprising a channel portion having a bottom and upstanding side walls, a pair of beveled rollers angularly inclined within said channel so that their beveled portion is directed into the corners formed by the meeting of the side walls with the bottom of

the channel, and said rollers being rotatably carried by a member pivotally and resiliently mounted and adapted to cause the beveled portions of said rollers to contact with the walls of the channel at said corners so that as a blade 5 and wrapper assembly passes along the channel with portions thereof horizontal and contacting with the bottom thereof and other portions upstanding and contacting with said side walls, said beveled rollers will form creases at the line of 10 junction horizontal portions of said wrapper with the upstanding portions thereof.

5. In a wrapping machine for safety razor blades, a guide channel construction for guiding a razor blade and wrapper assembly comprising 15 a channel having bottom walls and side walls, and a guide member carried by each side wall and having portions disposed in parallel relation to said side walls and spaced so as to permit a portion of the wrapper to pass therebetween 20 and the side wall, and having other portions disposed in parallel relation to said bottom walls and spaced therefrom so as to barely permit said assembly to pass therebetween, said last-named portions being provided with upwardly directed guide portions for providing a gradual approach to the entrance of the assembly into the channel.

6. A guide channel construction for guiding a razor blade and wrapper assembly comprising 30 laterally spaced bottom members for said channel, advancing means positioned for reciprocation within the space between said members, and having means engaging said assembly for the purpose of advancing the same, side walls up- 35 standing from said members and defining the sides of a channel wide enough to receive a blade and wrapper assembly, and guide elements carried by each of said side walls, said guide elements each comprising an upstanding portion 40 parallel to one of said side walls and spaced therefrom sufficiently to receive a portion of the wrapper while said portion is in upstanding position and each of said elements also having a horizontally disposed terminal section disposed in 45 parallelism to said bottom members and provided with an upwardly curved extension at its forward end adapted to engage a portion of the wrapper at the front of the assembly and to fold the same in overlying relation to the assembly 50 and to hold it in said overlying relation.

7. A guide channel construction for guiding a razor blade and wrapper assembly comprising laterally spaced bottom members for said channel, advancing means positioned for reciprocation within the space between said members, and having means engaging said assembly for the purpose of advancing the same, side walls up- 55 standing from said members and defining the sides of a channel wide enough to receive a blade and wrapper assembly, and guide elements carried by each of said side walls, said guide elements each comprising an upstanding portion parallel and adjacent to one of said side walls and spaced therefrom sufficiently to receive a 60 portion of the wrapper in the space therebetween while said wrapper portion is in upstanding position.

8. In combination, a member adapted to receive a razor blade and wrapper assembly in 70 which the wrapper has a body portion and flaps projecting therefrom, in which the body portion of the wrapper overlies one side of the blade, and in which the line of juncture of the body of the wrapper and a flap constitutes the advancing 75

- edge, said member being adapted to invert the assembly so that the bottom thereof becomes the top and the trailing edge becomes the leading edge, means active while said assembly is being inverted, for folding the remaining flaps of the wrapper into a position perpendicular to the blade, a guide channel along which the blade and wrapper assembly may advance, means associated with such channel for retaining two of said flaps of the wrapper in said perpendicular position and for folding down the other flaps thereof, means for crossing the juncture of the perpendicularly positioned flaps with the body portion of the wrapper so as to cause them to fold 10 accurately along predetermined lines, and means for causing the downward folding of said perpendicularly positioned flaps so as to cause them to overlie the blade, said means comprising lateral guide grooves associated with said channel, said 15 grooves having opposed walls converging toward the side walls of the channel, the degree of convergence of said walls gradually decreasing to a position of parallelism and means near the entrance of said last grooves and positioned in the 20 channel between said grooves, whereby one of said perpendicular flaps will be prevented from assuming a position overlying the blade until the other perpendicular flap has first assumed its 25 overlying position.
9. In combination, a member adapted to receive a razor blade and wrapper assembly in which the wrapper has a body portion and flaps projecting therefrom, in which the body portion of the wrapper overlies one side of the blade, and 30 in which the line of juncture of the body of the wrapper and a flap constitutes the advancing edge, said member being adapted to invert the assembly so that the bottom thereof becomes the top and the trailing edge becomes the leading 35 edge, means active while said assembly is being inverted, for folding the remaining flaps of the wrapper into a position perpendicular to the blade, a guide channel along which the blade and wrapper assembly may advance, means associated with such channel for retaining two of said 40 flaps of the wrapper in said perpendicular position and for folding down the other flaps thereof, and means for causing the downward folding of said perpendicularly positioned flaps so as to 45 cause them to overlie the blade, said means comprising lateral guide grooves associated with said channel, said grooves having opposed walls converging toward the side walls of the channel, the degree of convergence of said walls gradually 50 decreasing to a position of parallelism and means near the entrance of said last grooves and positioned in the channel between said grooves, whereby one of said perpendicular flaps will be prevented from assuming a position overlying the 55 blade until the other perpendicular flap has first assumed its overlying position.
10. In mechanism for wrapping razor blades, a guide channel for conducting a blade and wrapper assembly, said channel comprising a 60 bottom surface and lateral members upstanding therefrom, said lateral members having grooves therein adapted to slidably engage the sides of a wrapper and blade assembly, and the walls of said grooves diverging outwardly, with the divergence 65 increasing toward the entrance of the channel and decreasing toward the end thereof, so that at the end of said grooves their walls are parallel, whereby lateral upstanding portions of the wrapper, as the assembly enters the channel, 70 will be gradually folded down until they assume 75 an overlying relation to the blade, means overlying the channel and positioned between the lateral members thereof, and spaced from the bed of the channel so as to permit the passage thereunder of a blade and wrapper assembly, and 80 spaced from said lateral members so as to permit the passage of lateral upstanding portions of the wrapper, and an element carried by said means and adapted to engage portions of one of said lateral upstanding portions and to prevent its being brought into overlying relation to the assembly by the action of the grooves of the lateral members until the other lateral upstanding portions have been brought into said overlying relation. 15
11. In mechanism for wrapping razor blades, a guide channel for conducting a blade and wrapper assembly, said channel comprising a bottom surface and lateral members upstanding therefrom, said lateral members having grooves therein adapted to slidably engage the sides of a wrapper and blade assembly, and the walls of said 20 grooves diverging outwardly, with the divergence increasing toward the entrance of the channel and decreasing toward the exit end thereof, so that at the exit end of said grooves their walls are parallel, whereby lateral upstanding portions of the wrapper, as the assembly enters the channel, 25 will be gradually folded down until they assume an overlying relation to the blade, and means, other than the walls of said grooves, for delaying the folding of certain of the upstanding portions until other portions have been folded into overlying relations. 30
12. In a wrapping machine: a rotatable member comprising a pair of laterally spaced spiders having opposed slots therein, and the slots of the spiders being in lateral registration, a jaw member slidably associated with one side of each slot in such a manner that its face is always substantially parallel to the other side of the slot and resilient means tending to urge said jaw member into contact with the said opposite side of the slot, whereby, when an article is inserted within said slots, it will be held therein by resilient friction. 35
13. In a wrapping mechanism, means to receive an article having a wrapper associated therewith, said wrapper being of such width in relation to said means that the sides and an end of the wrapper protrude from said means, and said means being movable, and a single unitary bending means positioned so as to engage the protruding portions of said wrapper when said article receiving means moves relatively to said bending means, said bending means comprising a portion adapted to engage and to bend the protruding end of the wrapper into perpendicular relation to the body of the wrapper, and said bending means also comprising other portions positioned in proximity to said first mentioned portion and adapted to engage and to bend the protruding sides of the wrapper after said end bending means has bent the end of the wrapper. 40
14. In a wrapping mechanism: means to receive an article having a wrapper associated therewith, said wrapper being so dimensioned that portions thereof protrude from said means, said means being movable, and a single unitary stationary bending means positioned so as to engage the protruding portions of said wrapper when said article receiving means moves relatively to said bending means, said bending means comprising a portion adapted to engage and to bend first one protruding portion of the wrapper into per- 45

pendicular relation to the body of the wrapper, and said bending means also comprising other portions adapted to engage and to bend other protruding portions of the wrapper immediately after said first-mentioned portions have been bent.

15. In a wrapping mechanism: rotating means adapted to receive an article having a wrapper associated therewith, said wrapper being so dimensioned that portions thereof protrude from said rotating means and stationary bending means positioned so as to engage the protruding ends of said wrapper when said article receiving means moves relatively to said bending means, said bending means comprising an arcuate portion closely contacting the peripheral portions of said rotating means and adapted to engage and to bend the protruding end of the wrapper into perpendicular relation to the body of the wrapper, and said bending means also comprising flat portions closely contacting the sides of said rotating means and adapted to engage and to bend the protruding side portions of the wrapper.

16. In a wrapping mechanism: a combination of parts adapted to complete the wrapping of a partly wrapped article having portions of the wrapper upstanding from the main body thereof, said combination comprising means for folding down one of said upstanding portions, adapted to receive and to guide the remaining upstanding portions of the wrapper therebetween, creasing means for creasing the wrapper along the junction of the body of the wrapper and the said remaining upstanding portions thereof, means for folding one of said remaining upstanding portions into engagement with said article and wrapper assembly, and means to fold the other upstanding portion down over said first-mentioned upstanding portion, and means to prevent the folding down of said second mentioned portion until said first mentioned portion is folded down.

17. In a wrapping mechanism, means for forming creases in a wrapper, said means comprising a channel portion having a bottom and upstanding side walls, a pair of beveled rollers angularly inclined within said channel so that their beveled portion is directed into the corners formed by the meeting of the side walls with the bottom of the channel, so that as a blade and wrapper assembly passes along the channel with portions thereof horizontal and contacting with the bottom thereof and other portions upstanding and contacting with said side walls, said beveled rollers will form creases at the line of junction of said horizontal portions of said wrapper with the upstanding portions thereof.

18. In a wrapping mechanism, a guide channel adapted to receive a partly wrapped article in which two extensions of the wrapper have been caused to assume an upstanding position in relation to the body thereof, means associated with said channel for retaining said extensions in their upstanding position, and for folding down the other flaps thereof, means for creasing the junction of the perpendicularly positioned flaps with the body portion of the wrapper so as to cause them to fold accurately along predetermined lines, and means for causing the downward folding of said perpendicularly positioned flaps so as to cause them to overlie the blade, said means comprising lateral guide grooves associated with said channel, said grooves having opposed walls converging toward the side walls of the channel, the degree of convergence of said walls gradually decreasing to a position of parallelism and means near the entrance of said last grooves and positioned in the channel between said grooves, whereby one of said perpendicular flaps will be prevented from assuming a position overlying the blade until the other perpendicular flap has first assumed its overlying position.
